UNITED STATES PATENT OFFICE.

PHILIP A. BROWN, OF KANSAS CITY, MISSOURI, ASSIGNOR TO HARLEY L. FERGUSON, OF KANSAS CITY, MISSOURI.

ELECTRIC SIGN.

Application filed December 31, 1921. Serial No. 526,192.

To all whom it may concern:

Be it known that I, Philip A. Brown, a citizen of the United States, residing at Kansas City, in the county of Jackson and State of Missouri, have invented certain new and useful Improvements in Electric Signs, of which the following is a specification.

My invention relates to electric signs adapted to be used for displaying advertisements and other matter in show windows and other suitable places.

In carrying out the invention, a relatively large drum is employed to carry a number of advertisements which are successively displayed at an opening in an adjacent frame, or wall as said drum revolves.

Relatively small individual signs are associated with the drum to call attention to the advertising or other matter carried by said drum.

Other features will hereinafter appear and in order that the invention may be fully understood, reference will now be had to the accompanying drawings, in which:

Fig. 1 is a perspective view of the invention.

Fig. 2 is a side elevation of the drum and its driving mechanism, the frame associated with said drum being in vertical section.

Fig. 3 is a broken plan view of the drum and its driving mechanism.

Fig. 4 is an enlarged sectional detail of a detent for holding the drum stationary after each step.

Fig. 5 is a side elevation of a flasher.

Fig. 6 is an end elevation of the flasher.

Fig. 7 is a cross section of one of the individual signs.

Fig. 8 is a diagram of the circuits and the flasher.

Referring now in detail to the different parts, 2 designates a frame or wall having a rectangular opening 4 and provided at its ends with ornamental pillars 6, surrounded by electric lamps 8.

10 designates a drum which is fixedly mounted upon a shaft 12 journaled in the upper ends of a pair of standards 14. In the present instance the drum 10 is of hexagonal configuration in cross section and each side is of proper size to enter the opening 4 in the frame 2, as disclosed by

Figs. 1 and 2. Each of the six corners of the frame is provided with longitudinal slideways 16 to receive interchangeable cards 18 containing advertising or other desired information.

The drum 10 is rotated step by step to bring each card 18 in position at the opening 4 by the following mechanism: 20 designates a worm wheel mounted upon a stub shaft 22 carried by one of the standards 14. Said worm wheel 20 is driven by a worm 24 which in turn is driven by an electric motor 26. One of the spokes of the worm wheel 20 is provided with a draw-bar 28 yieldably mounted on a stud 30 and normally drawn outwardly by a coil spring 32 secured at its ends to the worm wheel 20 and said draw-bar 28.

The outer end of the draw-bar 28 is provided with a laterally projecting stud 34 to successively engage the slotted portions 40 of a wheel 42, fixed beside the drum 10 on the shaft 12. The slots 40 are radially disposed and equal in number to the sides of the drum 10.

44 designates a stop yieldably mounted in a guide 46 carried by a bracket 48 secured to the adjacent standard 14. Said stop 44 is normally pressed outwardly against the wheel 42 by a spring 50.

With the foregoing construction it is evident that while the worm 20 revolves continuously, it through the intermediacy of the detent 28 revolves the wheel 42 and the drum 10 step by step to successively bring the signs on the drum 10 in position for display at the opening 4 in the frame 2. As the pin 34 passes out of engagement with the wheel 42 the same is held stationary by the stop 44, which is forced into the registering slot 40 by the spring 50. Should the drum be turned by hand for any reason while the worm wheel 20 is stationary no damage will occur either to said pin 40 or the stop 44, as they may be forced inwardly against the action of the respective springs 32 and 50 by the wheel 42.

Referring now to the electrical apparatus, 54 designates a flasher associated with the opposite end of the drum 10 from the driving mechanism above described. Said flasher 54 embodies a disk 56 of insulation fixedly mounted upon the shaft 12 and provided at its periphery with segmental contacts 58, 60, 62, 64, 66 and 68 connected in series 105 110

by conductors 70. Some of the contacts are of different widths and the face of the contact 62 is divided into members 62^a and 62^b. The face of the contact 66 is divided by insulation into members 72 and 74, while the face of the contact 68 is divided by insulation into members 76 and 78.

The flasher 54 also includes a plurality of brushes 80, 82, 84, 86 and 87, the first four brushes being arranged side by side and diametrically opposite the brush 87. The brushes are secured to blocks of insulating material 88 fixed to a bracket 89 secured to the adjacent standard 14.

15 The brush 80 is connected by a wire conductor 90 to a main 100, while the brush 87 is connected by a wire conductor 102 to a main wire 104. The wire conductor 90 is connected to the poles of a flash light 106, mounted at the central, upper portion of the frame 2, the lamps 8 of which are connected in series by a wire conductor 108 connected across the mains 100 and 104.

16 The brush 82 is connected to the main 100 by a wire conductor 110, which is connected to the poles of a lamp 112.

17 The brush 84 is connected in parallel with the brushes 80 and 82 by a wire conductor 114, which is connected to the poles of a lamp 116. The brush 86 is connected in parallel with the brushes 80 to 84, inclusive, by a wire conductor 117, which is connected to the poles of a lamp 119.

18 By reference to Figs. 5 and 6, and the diagram Fig. 8, it will be understood that each time the drum 10 pauses one of the segmental contacts of the flasher 54 will be in engagement with the brush 80, while a diametrically opposed contact will be in engagement with the brush 87, thus establishing a circuit from the main 100 to the main 104 through the wire 90, the flash light 106, the segmental contacts on the disk 56, the conductors 70, the brushes 87, and the wire conductor 102.

19 When the flasher 54 stops with the contact member 78 in engagement with the brush 82, a circuit will be established from the main 100 to the main 104 through the wire conductor 110, the lamp 112, the brush 82, the segmental contacts and the conductors 70, the brush 87, and the wire 102.

20 When the flasher 54 stops with the contact member 74 in engagement with the brush 84, the circuit just above described will be established, excepting that that portion of the wire conductor 110 including the brush 82 and the lamp 112 will be cut out, while the lamps 116 and the wire 114 will be connected in.

21 When the contact member 62^b stops in contact with the brush 86, the lamp 119 and wire 117 will be connected in and the lamps 112 and 116 cut out.

22 During each step by step movement of the

drum 10 all of the circuits above described are cut out, excepting that in which the lamps 8 are located, said lamps 8 continuing to glow until the switch 120 is opened.

23 The lamps 112, 116 and 119, illuminate 70 the individual signs 122, each of which consists of oblong boxes 124 having grooves 126 in its upper portion to receive a glass or other interchangeable slide 128, which contains the advertising or other matter 75 which is brought prominently into view each time the lamp in the box glows.

24 From the foregoing description it will be understood that I have provided an apparatus whereby advertising or other matter 80 can be prominently displayed, and which matter can be readily changed from time to time as desired; and while I have shown and described the preferred construction, combination and arrangement of parts, I reserve the right to make such changes as properly fall within the spirit and scope of the claims.

25 Having thus described my invention, what I claim and desire to secure by Letters Patent, is:

1. In an apparatus of the character described, a drum for displaying advertising and other matter, mechanism for rotating said drum step by step, an electric lamp for illuminating the matter displayed by the drum, relatively small individual signs placed in advance of the drum, lamps for illuminating said individual signs, circuits for the lamps, and a flasher actuated by the drum and which makes and breaks said circuits.

2. In an apparatus of the character described, a drum for displaying advertising or other matter, a disk fixed to said drum and having radial slots, a driven wheel, a draw bar carried by said wheel and adapted to successively enter the radial slots to move the disk step by step, a stationary support, and a spring-pressed stop to successively enter the radial slots as the disk moves the distance of each step.

3. In an apparatus of the character described, a drum adapted to carry display matter, mechanism for intermittently rotating said drum, individual display means spaced from said drum, and means for illuminating a different individual display means during each pause of the drum.

4. In an apparatus of the character described, a drum adapted to carry a plurality of signs, mechanism for rotating said drum step by step to successively bring the signs in position to be displayed, individual display signs each of which has subject matter related to a sign on the drum, and intermittent means for illuminating each sign on the drum as it reaches the display position and for illuminating the individual sign related to the sign in display position on the drum.

5. In an apparatus of the character described, a drum adapted to carry a plurality of signs, mechanism for rotating said drum step by step to successively bring the signs 5 in position to be displayed, individual display signs each of which has subject matter related to a sign on the drum, a lamp for illuminating each sign displayed by the drum, a lamp for illuminating each individual 10 sign, circuits for the lamps, and means for

closing the circuit to the drum lamp and a circuit of the lamp of the individual sign related to the sign in display position on the drum during each pause of said drum.

In testimony whereof I affix my signature, ¹⁵ in the presence of two witnesses.

PHILIP A. BROWN.
